UNITED STATES PATENT OFFICE.

SEVERIN J. HANSON AND GUNDEE B. HANSON, OF HILLSBORO, NORTH DAKOTA.

DRILL-SHOE.

1,070,031.

Specification of Letters Patent. Patented Aug. 12, 1913.

Application filed February 8, 1912. Serial No. 876,177.

To all whom it may concern:

Be it known that we, SEVERIN J. HANSON and GUNDEE B. HANSON, citizens of the United States, residing at Hillsboro, in the county of Traill, State of North Dakota, have invented certain new and useful Improvements in Drill-Shoes; and we do hereby declare the following to be a full, clear, and exact description of the invention, such as will enable others skilled in the art to which it appertains to make and use the same.

This invention relates to new and useful improvements in drill shoes.

A great disadvantage heretofore experienced in using drill shoes of ordinary type is the clogging of loose straw or weeds in front of the shoe which lifts the drilling terminal out of the ground and causes the seeds to be deposited on top of the loose earth. This is also the case in wet weather or when the drill is used in heavy earth.

The object of this invention is to overcome this difficulty by constructing a drill shoe in such a manner that it will be difficult for weeds or straw to clog in front of the same and also one which will be comparatively simple and inexpensive to manufacture, reliable and efficient in use and readily operated.

With the above and other objects in view, this invention resides in the novel features of construction, formations, combinations and arrangements of parts to be hereinafter more fully described, claimed and illustrated in the accompanying drawings, in which:

Figure 1 is a side elevation of our invention. Fig. 2 is a rear elevation thereof. Fig. 3 is a horizontal sectional view taken on the line 3—3 of Fig. 1. Fig. 4 is a perspective view of one end of the drill shoe, and Fig. 5 is a side elevation of one of the plates removed.

Referring to the accompanying drawings by similar characters of reference throughout the several views, the numeral 10 designates generally our improved drill shoe which consists of the usual casing 11 formed with the customary vertical bore 12 which extends through the opposite ends thereof. The upper end of the casing 11 is provided with a rearwardly extending ear 13 for connection with the customary lifting chains (not shown on the drawings) while the opposite end of the said casing is formed with

a similar ear 14 for engagement with the usual drag chains which are also omitted from the drawings as the same have no bearing upon the invention. The lower end of the casing 11 is formed with a forwardly extending tapered web 15 which extends from the gage shoulder 16 to a point equally distant upon the opposite side of the lower terminal of the said casing 11 as is clearly illustrated in Fig. 1 of the drawings. The rear edge 17 of the extended portion of the web 15 projects in substantially parallel relation to the bore 12 flush with the forward side thereof. A pair of drill plates 18 are secured to the opposite sides of the web 15 and have their upper edges contacting with the shoulder 16 which assists in retaining the same against any undesired displacement. The upper edges of the plates 18 extend flush with the rear side of the drill shoe 10 as indicated by the numeral 19 for a considerable distance at which points they are beveled forwardly as at 20 to the lower point of the web 15. The forward edges of the plates 18 extend from the lower point of the web 15 forwardly and upwardly as at 21 conforming in curvature to the lower forward side of the web 15 and are secured together in any suitable manner to produce a cutting edge 22. The upper ends of the plates 18 are extended forwardly as at 23 and provided with a series of slitting apertures 24 for adjustable connection with the metal adjusting straps which connect the said drill shoe to a drill of any ordinary type and which is omitted from the drawings as the same has no bearing upon the invention.

From the foregoing disclosures taken in connection with the accompanying drawings it will be manifest that a drill shoe of the nature described is provided which will fulfil all of the necessary requirements of such a device.

It should be understood in this connection that various minor changes in the details of construction can be resorted to within the scope of the appended claim without departing from or sacrificing any of the advantages of the invention.

Having thus fully described this invention what we claim as new and desire to protect by Letters Patent, is:

In combination, a drill shoe comprising a casing having a bore terminating at its lower end in a rearwardly inclined portion,

said shoe terminating at the bottom in a forwardly extending tapered web projecting below the lower edge of the casing, the said lower edge being inclined to form a gage shoulder, said web being extended downwardly to form a continuation of the rear portion of said bore and drill plates secured to the opposite sides of said webs, said plates having upper edges contacting with the bottom edge of said casing, and meeting forwardly at an angle, said plates

further having forwardly extending portions adapted for attachment to an adjusting strap.

In testimony whereof, we affix our signatures, in presence of two witnesses.

SEVERIN J. HANSON.
GUNDER B. HANSON.
